UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed June 7, 1923. Serial No. 643,874.

This invention relates to internal combustion engines, and more particularly to the valve mechanism thereof.

It has for an object to provide an engine 5 in which a maximum valve port area is made available by the use of pairs of similar valves, arranged to operate in unison.

Another object of the invention is to provide a simple and compact valve mechanism 10 by which a pair of valves may be simultaneously actuated from a single cam.

Other objects of the invention will appear from the following description, taken in connection with the drawings which form a 15 part of this specification, and in which:

Fig. 1 is a vertical section through the upper portion of an internal combustion engine equipped with the invention, and

Fig. 2 is a plan view of the engine shown 20 in Fig. 1, partially in section on the line 2—2 thereof.

The advantages of large valve port area have been recognized in internal combustion engine practice, and it has been heretofore 25 proposed to substitute for one intake and one exhaust valve in each of the engine cylinders, pairs of similar valves, each of smaller diameter, but of greater combined area. Under the high engine speeds now 30 practiced, lack of synchronism seriously affects the gain in port area otherwise acquired by such plural valve structure, and difficulties have arisen in effecting simultaneous operation of such valves. This invention 35 provides a simple connection between valves of such pairs by which they are actuated in absolute unison.

Referring to the drawing, at 10 is shown 40 an internal combustion engine having a cylinder 11, equipped with the usual piston 13, and carrying a head 12, which is provided with duplicate exhaust passages 14, one on each side thereof, and similar intake passages (not shown). These intake and exhaust passages are adapted for connection 45 respectively with the usual intake and exhaust manifolds (not shown), there being both an intake and an exhaust manifold on each side of the engine, as is well understood.

The head 12 is provided with pairs of 50 similar valves 16, of the well known poppet type, of which one pair is adapted to control the intake of fuel mixture to the engine cylinder, and the other pair is adapted to per-

mit the expulsion of exhaust gases therefrom. As the construction and operation of the mechanism for these two sets of valves is in all particulars identical, only the exhaust valve structure will be herein described.

The valves 16 are provided with upwardly extending stems 17, mounted in suitable bushings 18 in the head structure 12. The stems 17 project through the upper end of the cylinder head proper, and are adapted for connection near their upper ends with the usual spring abutments 19, which co-operate with springs 21, bearing on the upper surface of the cylinder head, which springs serve to urge the valves 16 against their seats 22 in the well known manner.

Surrounding the valve stems 17 is an upwardly projecting lug 23, preferably integral with the cylinder head 12, and bored to form cylindrical guides 24, which are coaxial with the valve stems 17. Slidably mounted in each of the guides 24 is a guide member 26, which is preferably of thin sheet metal, drawn into the form of a cup, and provided on its upwardly disposed face 27 with a boss 28. The bosses 28 are drilled and threaded for cooperation with tappet screws 29, the lower ends of which contact the ends of the valve stems 17. The upper ends of the tappet screws 29 are slotted, as at 30, to facilitate their axial adjustment with respect to the bosses 28.

A horizontally disposed yoke member 31 is arranged to rigidly connect the guide members 26. This yoke member 31 has preferably two similar end portions 32, and an intermediate portion 33 of greater thickness. The end portions 32 are each provided with an opening 34 adapted to embrace the upwardly disposed boss 28 on the guide member 26. The lower face of the yoke member 31 rests upon the upper face of the guide member 26 and these members are clamped together by a washer and nut 100 assembly 36, threaded on the extremities of the tappets 17. The intermediate portion 33 of the yoke member 31 has an upwardly disposed face 37, in a plane above the end portions 32, which provides a follower surface 105 for coaction with the operating means. As shown, this operating means comprises a cam shaft 38, arranged above the engine and provided with suitable cams 39 which bear against the follower surface 37. It is to be 110

understood, however, that push rods, rocker arms, or any other suitable operating mechanism may be employed to actuate the yoke member 31.

5 In the operation of the invention, rotation of the cam shaft 38 causes the cams 39 to move the follower 37 downward, the yoke member 31 exerting a simultaneous pressure on each of the valve stems 17 through the 10 tappet screws 29, against the pressure of the springs 21, to open the valves 16 in unison. Continued rotation of the cam shaft 38 causes the cam 39 to release the follower 37 in the familiar manner, the valves, tappets, 15 guide members and yoke being returned to their initial position by the springs 21.

The guide members 26 receive all side thrust that is communicated to the yoke member 31 by the cam 39, and transfer it to the guides 24, where it is absorbed, so that the valve stems 17 work freely in their guides 18 without any tendency to bind therein.

20 The guide members 26, being rigidly connected by the yoke member 31, reciprocate in the guides 24 as a unit, and because of their extensive bearing surface are free from binding and twisting therein. In this manner synchronous and equal travel of the 25 valves 16 is ensured, and the advantages of the plural valves fully realized.

It will be understood that various forms 30 of the invention other than those described above may be used without departing from the spirit or scope of the invention.

35 What is claimed is:

1. In combination in an internal combustion engine, a pair of poppet valves, a yoke member, guide means surrounding the stem 40 of each valve detachably secured to the yoke member, and a cam adapted to actuate the yoke member to operate the valves in unison.

2. In combination in an internal combustion engine, having a head, a pair of poppet 45 valves in the head, a pair of guide members having bosses, means adjustable in said bosses adapted to actuate the stems of said 50 valves, guides on the head cooperating with each guide member, a yoke member removably secured to each of the guide members by said adjustable means, and a cam adapted to actuate each yoke member to operate the valves in unison.

3. In combination in an internal combustion engine, having a head, a cam, a pair 55 of poppet valves in the head, guide means associated with each valve including guides on the head and guide members reciprocable therein, and a yoke securing the guide members together having end portions disposed

above the respective valves and an intermediate portion constituting a follower for co-action with the cam.

4. In an internal combustion engine having a head, a cam, a pair of poppet valves, a yoke member having a portion adapted 65 for cooperation with the cam, and guide means secured to the yoke including guides integral with the head and guide members therein having bosses adapted to actuate the stems of the valves and connected to the end portions of the yoke member.

5. In an internal combustion engine having a head, upwardly disposed guides on the head, cylindrical guide members adapted 70 for reciprocation in the guides and having upper faces provided with bosses, poppet valves in the head having upwardly disposed stems, tappet members bearing on the stems threaded to the bosses, a yoke member 75 having end portions apertured to receive the bosses and an intermediate portion providing a flat surface above the plane of the end portions, threaded means on the tappet members clamping the yoke member to the 80 bosses, and a cam contacting the flat surface of the yoke member to actuate the valves in unison.

6. In an internal combustion engine, the combination with the head thereof, upwardly disposed guides on the head, guide members adapted for reciprocation in said guides, poppet valves in the head, tappet members adjustable in said guide members and bearing on the stems of said valves and 90 a yoke member secured to said guide members by the tappet members.

7. In an internal combustion engine, the combination with the head thereof, upwardly disposed guides on the head, guide members adapted for reciprocation in said guides, poppet valves in the head, tappet members adjustable in said guide members and bearing on the stems of said valves, a yoke member, and means securing said yoke 100 member and tappet members to the guide members.

8. In an internal combustion engine, the combination with the head thereof, upwardly disposed guides on the head, guide members adapted for reciprocation in said guides, poppet valves in the head, tappet members adjustable in said guide members and bearing on the stems of said valves, a yoke member, and means on the tappet members 110 for securing said yoke members to the guide members and locking the tappet members in position.

In testimony whereof I affix my signature.

LIONEL M. WOOLSON.
